US00D572578S

(12) **United States Design Patent**
Sato et al.

(10) **Patent No.:** US D572,578 S
(45) **Date of Patent:** ** Jul. 8, 2008

(54) **ELASTIC MEMBER OF AN ELASTIC COUPLER**

(75) Inventors: **Yoshiyuki Sato**, Tokyo (JP); **Nobushige Fujioka**, Tokyo (JP); **Satoshi Kimura**, Tokyo (JP)

(73) Assignee: **Miki Pulley Co., Ltd**, Kanagawa (JP)

(**) Term: **14 Years**

(21) Appl. No.: **29/262,525**

(22) Filed: **Jul. 5, 2006**

(51) **LOC (8) Cl.** 08-08

(52) **U.S. Cl.** D8/382

(58) **Field of Classification Search** D8/382, D8/383; 403/403, 322.4, 322.1, 217; 464/73, 464/88

See application file for complete search history.

(57) **CLAIM**

The ornamental design for an elastic member of an elastic coupler, as shown and described.

DESCRIPTION

FIG. 1 is a perspective view of an elastic member showing our new design;

FIG. 2 is a front view thereof;

FIG. 3 is a right side view thereof, a left side view being a mirror image thereof;

FIG. 4 is a top view thereof, a bottom view being a mirror image thereof;

FIG. 5 is a back view thereof; and,

FIG. 6 is a cross-sectional view thereof taken along the line VI—VI in FIG. 2.
